(57) **CLAIM**

The ornamental design for a connecting rod, as shown.

DESCRIPTION

FIG. 1 is a perspective view of the connecting rod.

FIG. 2 is bottom perspective view of the connecting rod of FIG. 1.

FIG. 3 is a top perspective view of the connecting rod of FIG. 1.

FIG. 4 is a bottom perspective view of the connecting rod of FIG. 1.

FIG. 5 is a front perspective view of the connecting rod of FIG. 1.

FIG. 6 is a back perspective view of the connecting rod of FIG. 1.

FIG. 7 is a left side view of the connecting rod of FIG. 1; and, FIG. 8 is a right side view of the connecting rod of FIG. 1. The stippled surface shading represents the surface appearance created by sand casting.

The broken line in FIG. 6 represents the boundary between claimed and unclaimed areas of the connecting rod which forms no part of the claimed design.

UNITED STATES PATENT AND TRADEMARK OFFICE
CERTIFICATE OF CORRECTION

PATENT NO. : D643,441 S
APPLICATION NO. : 29/318557
DATED : August 16, 2011
INVENTOR(S) : Christian Knobloch et al.

Page 1 of 1

It is certified that error appears in the above-identified patent and that said Letters Patent is hereby corrected as shown below:

On the Title Page, Item (57)

In the Description preceding the claim, delete "The broken line in FIG. 6 represents the boundary between claimed and unclaimed areas of the connecting rod which forms no part of the claimed design." and insert --The broken lines showing unclaimed portions of the connecting rod form no part of the claimed design.--.
